UNITED STATES PATENT OFFICE.

JOHN R. SCHELOSKY, OF ST. LOUIS, MISSOURI.

DESIGN FOR A BLOCK FOR EXTENSION-TABLE SLIDES.

SPECIFICATION forming part of Design No. 28,069, dated December 21, 1897.

Application filed September 17, 1897. Serial No. 652,076. Term of patent 14 years.

To all whom it may concern:

Be it known that I, JOHN R. SCHELOSKY, of the city of St. Louis, State of Missouri, have invented a new and original Design for a Block for Extension-Table Slides, of which the following is a full, clear, and exact description, reference being had to the accompanying drawings, forming a part hereof.

Figure 1 is a view in perspective of a block embodying my design, and Fig. 2 is a perspective of the block turned bottom upward.

As shown in the drawings, the leading or material feature of my design consists of a block having parallel end faces, parallel side faces three or four times as long as the end faces, a lower face in the form of a groove, the faces forming said groove being of equal dimensions and arranged at angles of approximately thirty degrees relative to a horizontal line, and an upper face in the form of an irregular groove, one of the faces forming said irregular groove being regular and identical with one of the faces forming the lower groove and the other one of said faces forming said irregular groove being offset relative to the regular face, thus forming a shoulder

at the center of said upper face and said offset face being cut away at one of its ends and the grain of the wood running crosswise of the block and crosswise of the grooves. 30

Referring by numerals to the drawings, 3 and 4 are the parallel end faces.

5 and 6 are the parallel side faces.

7 and 8 are the faces forming the grooved lower side.

9 is the regular face of the upper side; 10, the irregular face of the upper side; 11, the shoulder between the faces 9 and 10; 12, the cut-away portion of the face 10, and 13 the grain of the wood, said grain running crosswise of the block and crosswise of the grooved faces. 35

I claim—

The design for a block for extension-table slides, substantially as herein shown and described. 45

In testimony whereof I affix my signature in presence of two witnesses.

JOHN R. SCHELOSKY.

Witnesses:

EDWARD E. LONGAN,
ALBERT J. McCUALEY.
